(57) **CLAIM**

The ornamental design for a “scrub top,” as shown and described.

DESCRIPTION

FIG. 1 is a right side, front perspective view of a scrub top showing my new design;

FIG. 2 is a front view of the scrub top of FIG. 1;

FIG. 3 is a right side view of the scrub top of FIG. 1;

FIG. 4 is a left side view of the scrub top of FIG. 1;

FIG. 5 is a rear view of the scrub top of FIG. 1;

FIG. 6 is a top view of the scrub top of FIG. 1; and,

FIG. 7 is a bottom view of the scrub top of FIG. 1.

The broken lines showing a stethoscope, ID badge, and pager in FIG. 1 is for illustrative purposes only and forms no part of the claimed design.

1 Claim, 6 Drawing Sheets

FIG. 1
